[57] CLAIM

The ornamental design for an automated teller machine, as shown and described.

DESCRIPTION

FIG. 1 is a front perspective view of an automated teller machine, showing my new design;

FIG. 2 is a front elevational view thereof; and,
FIG. 3 is a right side elevational view thereof, the left side view being a mirror image thereof.

The rear elevational view is generally plain and unornamented.

FIG. 1

FIG. 2

FIG. 3
